William E. Holt, % Holt Mfg. Co., 10702 46th St.,
Tampa, Fla.

Filed Feb. 26, 1962, Ser. No. 68,988

Term of patent 14 years

(Cl. D9—2)

FIG. 1 is a side elevation of a combined portable vacuum cleaner tank and accessory basket, showing my new design; the broken lines in FIG. 1 being for illustrative purposes only; the side not shown is substantially the same in appearance as the side shown; and

FIG. 2 is a top view thereof.

I claim:

The ornamental design for a combined portable vacuum cleaner tank and accessory basket, as shown and described.
